METHOD OF AND APPARATUS FOR SUPER-HEATING OIL IN VAPOR PHASE

Frank H. Praeger, Bala-Cynwyd, and Thomas B. Leech, Narberth, Pa., assignors to Alcorn Combustion Company, Philadelphia, Pa., a corporation of Delaware

Application June 9, 1938, Serial No. 212,850

8 Claims. (Cl. 196—110)

Our invention relates to methods of and apparatus for superheating oil in vapor phase, and has for an object the provision of a simple reliable and inexpensive means of superheating oil vapors in oil-conducting heat-absorbing tubes with a minimum pressure drop.

In a great many methods of processing hydrocarbons (herein referred to as "oil") and their derivatives, it is necessary to superheat the oil vapors. This is ordinarily done by passing the oil in liquid phase to a vapor separator, where the pressure is reduced to produce as much vaporization as possible. To maintain the pressure as low as possible within the separator, and thereby increase the percentage of oil vaporized, we connect the vapor outlet of the separator to a bank of heat-absorbing tubes which, in accord with our invention, is so constructed and arranged as to have an exceedingly low pressure drop, thus permitting a low pressure within the separator; lower than heretofore possible, since less pressure differential is required to produce forced flow of a given throughput through the tubes.

Though the pressure is low, the pressure differential is still such as to insure a sufficiently high velocity within the tubes for good heating conditions.

Further in accord with our invention, the cost of the pumping equipment is greatly reduced for the same throughput, since the pressure drop within the heating system is quite low.

In accord with a further aspect of our invention, the vapors are superheated while forced with a low pressure drop through a plurality of vapor-conducting heat-absorbing tubes connected in parallel, with substantially equal elevation of temperature of the several vapor streams.

In carrying out our invention in one form thereof, the oil in liquid phase is elevated in pressure, heated above its vaporization temperature, flashed, and the vapors then conducted to a heating system where they are superheated. To reduce the pressure drop and thereby maintain a low pressure within the separator, we provide one or more banks of tubes with all of the tubes of each bank connected in parallel with each other; specifically by means of headers whose cross-sectional areas vary in accord with the volume of vapor passing therethrough. More specifically, from the inlet at one end of one header, the cross-sectional area decreases to the opposite end thereof, roughly in the proportion of the decrease in tubes served by the header at any given point to the end opposite the said inlet. The opposite header of like cross-section

is arranged so that its cross-section increases from one end to the opposite end; the latter end forming the outlet from the bank of tubes. In this manner every vapor particle from inlet to outlet of the bank traverses exactly the same distance as every other particle, regardless of the tube or path taken; and the parallel streams of vapor are elevated in temperature by substantially like amounts, since the volume, or mass-velocity of vapors through each tube is substantially equal to the mass-velocity through every other tube. Additionally, the tubes of each bank are preferably disposed in a row, adjacent the roof and floor of a heating chamber within which is projected intermediate the banks, currents of hot combustion gases. The bank of tubes adjacent the floor is disposed below and without the currents of hot gases, and each of its tubes receives heat substantially solely by radiation with high and substantially uniform heat input to the tubes of that bank; and the heat input or rate of heat transfer per unit area of heat-absorption surface per unit time as between the roof and floor-tube banks is or may be of the same order of magnitude so that the heat inputs or rates as between the opposed banks are substantially the same.

For an illustration of one form of our invention, reference is to be had to the accompanying drawings in which:

Fig. 1 is a combined vertical sectional view of heat-transfer apparatus embodying our invention, with diagrammatic representation of the mode of its operation in a typical process;

Fig. 2 is a plan view, taken on the line 2—2 of Fig. 1 of one heat-absorption structure;

Fig. 3 is an enlarged horizontal sectional elevation of one of the headers of Fig. 1; and

Figs. 4, 5 and 6 are sectional elevations of the header of Fig. 3, and are respectively taken on the lines 4, 5 and 6 of Fig. 3.

Referring to the drawings, we have shown our invention in one form as applied to an oil-cracking system in which the charge oil, supplied to the system by line 10, is elevated in pressure by a charge-pump 11 to insure rapid flow of the oil through a bank of tubes 12 disposed in the convection section C of a furnace or heater 14. After passage through the tubes 12, connected either in series or parallel, the oil, elevated to desired vaporization temperature, is discharged by line 15 into a vaporizing chamber 16. Before introduction into the vaporizing chamber 16, the pressure of the oil may be reduced by means of a

valve 17. In a manner well understood by the art, the oil in vaporizing chamber 16 is separated into vaporous and liquid components. The liquid component may be withdrawn by line 18, under the control of valve 19, and discharged from the system by line 20, or preferably used as reflux, or returned to a heating coil for further elevation of temperature.

The vapors, still under substantial pressure and well above atmospheric pressure, are withdrawn from the chamber 16 by line 22 and introduced into the inlet 23a of a header 23. As shown, the header 23, in conjunction with a second header 24, connects in parallel a plurality of oil-conducting heat-absorbing tubes 25, ten of them being shown in the drawings, though more or less than ten may be used.

After passage through the tubes 25, disposed horizontally adjacent the roof of fire chamber R, the vapors are discharged through the outlet 24b of the roof-tube bank, and by means of a connecting line 26 are introduced into the inlet 27a of a header 27, which, in conjunction with a header 28, serves to connect in parallel a plurality, as ten, heat-absorbing tubes 29, all horizontally disposed adjacent the floor of fire chamber R. The vapors are discharged from the floor-tube bank 29 by means of outlet 28b, and by transfer line 30 they are conducted to other apparatus for further processing, which apparatus is diagrammatically indicated at 31. This additional apparatus is not illustrated in detail, since it may be of the conventional type well known to those skilled in the art, and may include the usual devices, such as bubble towers and condensers, for separating and liquefying products desired as motor fuel.

To generate heat, a plurality of muffles or combustion chambers 32 are disposed horizontally along one wall of the fire chamber R. Fuel of any suitable character, preferably oil and/or gas, is introduced through the Venturi throat 33, together with the necessary air required for combustion. The fuel is partially, or to substantial extent, burned within the muffles 32. The hot, and burning gases, are discharged by the muffles 32 horizontally over and above the bank of floor tubes 29, which are disposed below and without the current thereof for absorption of heat substantially solely by radiation from the gases and refractory.

We prefer so to control the fuel pressure, the draft, and firing conditions, that the burning fuel issuing from the muffles passes substantially entirely above and across the floor tube bank, convectively heating the exposed surface of bridge wall 35, before transfer of heat by convection to tubes 12. Some of the hot gases, due to their tendency to rise, may to some extent convectively heat the roof tubes 25. The gases, after transfer of heat by convection to the tubes 12, are withdrawn to stack through the outlet passage 37.

In accord with our invention we reduce the pressure drop by subdividing the oil in vapor phase, introduced at 23a, into a plurality of streams, the ten streams shown being by way of illustration only, and not by way of limitation. By so reducing the pressure drop within the heating system, a much lower pressure may be maintained within the vapor separator 16 to produce a maximum vaporization of the oil in liquid phase therein. With said reduced pressure-drop and forced-flow of vapors, we equalize the flow, the pressure drop, and the rise in temperature

between each of the subdivided streams by progressively decreasing the cross-sectional area of the header 23 from the inlet side, as the vapor stream is progressively subdivided by the parallel-connected tubes 25, and by progressively increasing the cross-sectional area of the receiving header 24 to the outlet side, as the aforesaid subdivided streams of tubes 25 are united within the header 24.

More specifically, and referring to Fig. 2, it is to be observed the tubes 29, interconnected by horizontally disposed headers 27 and 28, are of equal length. The cross-sectional area of the vapor passage of header 27 progressively decreases from its inlet end 27a to its opposite end 27c, and the decrease is in proportion to the increase in the number of tubes receiving vapor as determined from right to left of the header as viewed in Fig. 2. Conversely, the cross-sectional area of the vapor passage within the header 28 progressively increases from its inlet end 28c to its outlet end 28b and in proportion to the increase in the number of tubes from right to left of header 28 as viewed in Fig. 2. By arranging the inlet 27a diagonally opposite the outlet 28b in conjunction with the aforesaid features, the oil in vapor phase may be forced through the bank of tubes with a minimum pressure drop, with an outlet pressure either above or below atmospheric pressure. Because of the number of tubes, the pressure drop between inlet and outlet is reduced to a minimum. By reducing the cross-sectional areas of the vapor passages, as described, we achieve a controlled flow of the vapors, and there is forced through each of the tubes an equal quantity of vapor.

Not only are the tubes 29 of equal length, but the several passages from inlet 27a to outlet 28b are all equal. Taking two extreme cases, a vapor particle may, from inlet 27a pass through the right-most tube 29 and thence through the full extent of the header 28 to its outlet 28b. On the other hand, a vapor particle may from inlet 27a traverse the full extent of header 27 and from the left-most tube 29 pass to the outlet 28b. The paths traversed by the vapor particles in the two cases are exactly equal to each other, and the resistance to flow of vapor in the two cases is equal. Similarly, for any intermediate tube 29, the length of the passage from inlet 27a to outlet 28b is exactly equal to the length of the passages of the two extreme cases just described; and equal to every other passage from inlet to outlet.

In accord with our invention, the pump 11, generally a costly piece of equipment, may for the same throughput be of much smaller size than has heretofore been the case, with a substantial saving, due to reductions in first cost, in maintenance, and in operation. The amount of power necessary to operate the pump 11 is reduced because the system is operated at a pressure materially lower than that required if the tubes were serially connected. By reason of the equalized flow between the tubes of each bank, there is no tendency for the flow to become concentrated within a few of the tubes, with concurrent reduction in quantity of vapor through the other tubes. If this were to occur, the tubes having the lesser amount of vapor would tend to overheat, with formation of coke or tarry deposits within the tubes. Also contributing to equalized flow is the arrangement of outlet and inlet of the headers at right angles to the tubes. This tends to diminish the effect upon the vapors of

their velocity which would be in a direction to cause unequal division between the tubes.

As applied to processing systems in which the oil in vapor phase is to be heated to high temperatures, but without substantial cracking of the vapors, it is particularly important that all of the vapors be equally heated, and none to a temperature producing cracking thereof. We have found that in accord with our invention, this desired result may be readily achieved, because equalized flow is maintained over wide changes in rates of flow, with the heat input or temperature rise of the vapor streams readily controlled in accord with the amount of fuel introduced into the fire chamber R by the muffles 32.

While each of the headers 23, 24, 27 and 28 may be circular in cross-section, we have shown one of said headers, the header 28 in Fig. 3, having a vapor passage which at the inlet end is, Fig. 4, circular in cross-section, and from the inlet end to its opposite end 28c, is in oval form gradually reduced in size as shown in Figs. 5 and 6.

A further feature of our invention consists in the provision of closures for the clean-out openings opposite each of the tubes which conform to the internal configuration of the header. The tubes are omitted in Fig. 3. In the preferred construction, these tubes are inserted within the openings 28d and are rolled against the header walls to form tight seals therewith. Opposite each tube is a plug or closure 40, shown as circular, whose internal surface, the surface presented to the interior of the header 28, forms a continuation of the inner wall of the header. In this manner, the inner surface of header 28 is smooth throughout, and there are no projections or recesses to produce eddies, or other variations in flow; nor is there any tendency for unequal division of the vapors between the plurality of tubes. Each closure 40 is provided with a circular flange 41, through which a series of cap screws 42 may extend into an opposing cooperating flange of the header, tightly to secure them in place. For simplicity, only the cap screws 42 for one of the closure members are shown. If desired, to reduce the weight of the closure members, they may be provided with re-entrant openings 43.

While we have shown a particular embodiment of our invention, it will be understood that we do not limit ourselves thereto, since many modifications may be made, and we, therefore, contemplate by the appended claims, to cover any such modifications as fall within the spirit and scope of our invention.

What we claim is:

1. A system of superheating oil in vapor phase comprising a heating chamber, means for producing a current of hot combustion gases within said chamber, a plurality of oil-conducting heat-absorbing tubes disposed adjacent the floor of said chamber below and without the current of said combustion gases, headers disposed horizontally and connecting said tubes in parallel with each other, the internal area of one header increasing from right to left across said bank and the internal area of the other header increasing from left to right across said bank, and transfer lines connected to said headers where the areas thereof are maximum.

2. In a system of superheating oil in vapor phase, the combination of a row of tubes disposed in substantially the same plane, headers receiv-

ing the opposite ends of said tubes for connecting them in parallel, the internal area of one header increasing from right to left and the internal area of the other increasing from left to right across said row of tubes, each of said headers having clean-out openings opposite the respective ends of said tubes, and closures for said clean-out openings, each said closure having a portion which forms, with the internal surface of said header, a smooth uninterrupted surface.

3. In a system of superheating oil in vapor phase, the combination of a row of tubes disposed in substantially the same plane, headers receiving the opposite ends of said tubes for connecting them in parallel, the internal area of one header increasing from right to left and the internal area of the other increasing from left to right across said row of tubes, said headers having walls including a flange forming a clean-out opening opposite each of said tubes, a closure for each of said openings including a flange cooperating with said flange of the walls forming each of said openings, each of said closures having a portion disposed within the said opening and of the same configuration as the inner surface of the header adjacent said opening.

4. The method of superheating oil in vapor phase which comprises forcing under elevated pressure a stream of oil in vapor phase from the inlet to the outlet of a heating system, reducing the pressure drop between said inlet and said outlet by subdividing said stream into a plurality of streams, equalizing the flow and pressure drop between each of said subdivided streams by passing said subdivided streams through paths, which paths, between said inlet and said outlet are of equal length, by progressively decreasing the cross-sectional area of the stream at the inlet side as that stream is progressively subdivided, and by progressively increasing the cross-sectional area of said stream at the outlet side as said subdivided streams are united.

5. A system of superheating oil in vapor phase comprising a pair of headers, a plurality of tubes in parallel with each other and interconnecting said headers, one of said headers from its inlet end having a vapor passage whose cross-sectional area progressively decreases and the other of said headers having a vapor passage whose cross-sectional area progressively increases to the outlet thereof, thereby to provide a plurality of passages of substantially equal length, as measured between said inlet and said outlet of said headers, means including a feed line connected to said inlet for producing forced-flow of said oil in vapor phase, and a discharge line connected to said outlet and within which are united the streams of oil in vapor phase flowing through said tubes.

6. A system of superheating oil in vapor phase comprising a heater, means for producing a current of hot combustion gases within said heater, a bank of tubes within said heater, and so disposed with respect to said current of gases that the individual tubes thereof are equally heated, a header, having an inlet at one end, connected to corresponding ends of the tubes, the cross-sectional area of said header progressively decreasing from its inlet end to its opposite closed end, a second header, having an outlet at one end, connected to the opposite ends of said tubes, the cross-sectional area of said second header increasing from its closed end to its outlet, and said second header so disposed with respect to said first header that the closed end thereof is opposite the largest cross-sectional area of the other

header, and means for producing flow under elevated pressure of said oil in vapor phase from said inlet of one to said outlet of the other of said headers.

- 5 7. A system of superheating oil in vapor phase comprising a heater, means for producing a current of hot combustion gases within said heater, a bank of tubes within said heater, and so disposed with respect to said current of gases that the individual tubes thereof are equally heated, a header, having an inlet at one end, connected to corresponding ends of the tubes, the cross-sectional area of said header progressively decreasing from its inlet end to its opposite closed end 10 inversely as the sum of the cross-sectional areas of the tubes increases from the inlet to closed end of the header, a second header, having an outlet at one end, connected to the opposite ends of said tubes, the cross-sectional area of said second header increasing from its closed end to its outlet, and said second header so disposed with respect to said first header that the closed end thereof is opposite the largest cross-sectional area of the other header, and means for producing 15 flow under elevated pressure of said oil in vapor phase from said inlet to said outlet of said headers.
- 20 8. A system of superheating oil comprising a tubular heater including a heating chamber,

means for producing therein a current of hot combustion gases, a bank of oil-conducting heat-absorbing tubes within said chamber, an oil-supply line, means for elevating the pressure of the oil in liquid phase and forcing the same at 5 high velocity through said bank of tubes, vaporizing means connected to said bank, a second bank of tubes adjacent the floor and a third bank of tubes adjacent the roof of said heater, the said current of hot gases passing between said second and third banks, headers for connecting the tubes of said second and third banks in parallel with each other, one header having an inlet for the tubes of one bank and the other having an outlet for said tubes, each said header provided with 10 said inlet having a vapor passage whose cross-sectional area decreases in the direction of vapor flow, and the other of said headers associated with each bank having a vapor passage whose cross-sectional area increases in the direction of 15 vapor flow, means for conducting oil in vapor phase from said vaporizing means to the inlet of one of said headers, means for connecting the associated outlet-header to the inlet-header of the other bank of tubes, and a transfer line connected to the outlet-header of said other bank of tubes. 20 25
